[57] CLAIM

The ornamental design for a combined holder for memo paper and vertical file, as shown and described.

DESCRIPTION

FIG. 1 is an upper, front perspective view of a combined holder for memo paper and vertical file showing my new design;

FIG. 2 is a lower, rear perspective view thereof;

FIG. 3 is a top plan view thereof;

FIG. 4 is a right side elevational view thereof;

FIG. 5 is a front elevational view thereof;

FIG. 6 is a left elevational view thereof;

FIG. 7 is a rear elevational view thereof, and,

FIG. 8 is a bottom plan view thereof.

FIG. 1.FIG. 2.FIG. 3.FIG. 4.FIG. 5.FIG. 6.FIG. 7.FIG. 8.
